UNITED STATES PATENT OFFICE.

B. A. MILLS, OF KEYSTONE, WEST VIRGINIA.

AUTOMATIC LINER SAFETY.

Application filed October 18, 1927. Serial No. 226,935.

The present invention relates to an attachable safety locking device for use in slug and type-casting machines to prevent breaking and damaging of mold liners by the ejector blade. This device fastens to the underside of the intermediate channel, the ejector dial lever, the vise locking screws and the mold turning pinion having locking and unlocking arrangements which move an obstruction into and out of the entrance of the intermediate channel automatically. It positively prevents damaging and breaking of mold liners by the ejector blade while the cams are rotating.

To the above and other ends, which will be found as the description proceeds, this invention resides in the arrangements of a combination of parts and in the details of its construction, hereinafter described and claimed.

The form of this invention is illustrated in the accompanying drawings, in which Fig. 1 is an interior view of the invention, Fig. 2 is a perspective view of a model of the invention connected with the vise locking screws U, the mold turning pinion V and the underside of the intermediate channel R being connected by brackets 15 and 34.

Referring in details to the drawing, the present invention has as its essentials:

A hood 36 (Fig. 1), extending from hood screw 10 and channel latch adjusting screw 11 to bracket 15 being held in position by hood screws and adapted to support a compression spring 1, justification lever 5 and a channel latch 3; a frame 8 (Fig. 1), containing a longitudinal channel extending from bracket 15 to hood screw 10, through which transfer blades 2, 4 and 14 extend. Transfer blade 2 is constructed in a sort of angular form having two fingers A and B; finger B is forced upward when finger A is released by lug 16 there being a torsion spring 1 at L (Fig. 1), connecting it with lug 17. The upward movement of said finger B brings it into engagement with lug C of a channel latch 3, raising it at F, there being an interposing coil spring in wall of said channel latch 3 at E. It is held in elevated position, closing said channel's entrance.

When the vise mechanism W (Fig. 2), of said slug and type-casting machines is opened for making changes of mold liners its trimming knife block or sector cover H is withdrawn from the justification lever leaving its end free from pressure so that the transfer blade A is not now controlled by lug 16

but by spring 1 by which blade B is swung to engage shoulder C and raise channel latch 3

The said channel latch 3 having been raised in the entrance of said intermediate channel it thereby prevents the line of matrices from going into the first elevator head unless it is withdrawn when the dial lever I is properly adjusted to bring projection 6 into engagement with lug D. This offers an obstruction at S (Fig. 2).

There is a long finger and delivery slide mechanism having a lower end starting roller which engages a starting clutch, located on the main cams of said slug and type-casting machine. The said cams are caused to rotate when said starting clutch is engaged by said starting roller, as the upper end of the long finger is moved by finger Q of the transfer slide which slides the matrices through the intermediate channel.

There are two supporting collars 21 and 22 (Fig. 2), with lugs A' and Y, being operatively connected with the vise locking screws U and a timing block 28 and also adapted to accommodate a reciprocal register rod 24. The reciprocal register rod is constructed with right and left sections being joined together by coupling 26 and set screws 12, its left section having angles and supporting a lock nut 32 situated near its lower end which is operatively connected with an adapter slide block 31, and its right section also having angles operatively connecting it with a timing block 28 and the intermediate transfer blade 4 (Fig. 1) and (Fig. 2). The adapter slide block 31 is constructed with a clearance at X through which the reciprocal register rod's left section's lower end extends. There are two adjusting screws 25 extended to the head of said mold turning pinion V being operatively connected with the said adapter slide block and adapted to regulate the forward movement of said lock nut 32. A compression spring 29 operatively connected with head of extension pin 23 and the said adapter slide block 31 adapted to move the adapter slide block inward whenever it is released by the said mold turning pinion. A small interposing coil spring 35 is situated in the inside wall of the adapter slide block 31 adapted to hold the said adapter slide block in upright position when it is out of engagement with the said lock nut 32.

An extension pivot pin 23 is adapted to support said adapter slide block 31 and springs 29 and 35 (Fig. 2).

The timing block 28 is held in position by screw 27 located at lug Y of supporting collar 22 (Fig. 2), having an aperture through which the said reciprocal register rod extends being adjustable to release said intermediate transfer blade at N (Fig. 2), by means of a compression spring 33 in the lower portion of said aperture and the adjusting screw 30 in head of said timing block.

10 Means are provided for holding the safety locking arrangement inoperative when casting folios or whenever desired. This holding means has as a part a member provided with a hook 18 and which is attached to the justification lever 5 at O. Plate 19 has perforations to adjustably receive hook 18 and a latch for attachment to frame T of the type casting machine. The adjustment provided between plate 19 and hook 18 adapts the holding means to various models of type-casting machines.

The unlocking arrangements comprise a dial lever key 6 which is adjustable at 9 (Fig. 1), adapting it for use on various models. An interchangeable transfer blade 14 being slotted at K accommodating a channel latch screw 7 which enables it to be drawn downward by said dial lever key 6 which is also operatively connected with said dial lever I which controls and changes the size of ejector blades, its lug D (Fig. 1) being engaged by dial lever key 6 when registering multiple 4 at I (Fig. 2).

This invention constitutes a positive and practical mold liner safety arrangement, automatic throughout. The operator may operate this device by raising the dial lever upward to size 4 then downward to the size of blade wanted. This should be done before the operator sends in his first line of matrices for each change of mold or mold liner made.

Having thus described the invention I claim:

1. In an automatic liner safety device, adapted to be attached to the lower side of the intermediate channel, the vise locking screws, the mold turning pinion and the dial lever, supporting brackets for end and front adapted to support a section of the device attachable to the intermediate channel, a channel latch located at the entrance of the intermediate channel and movable into and out of the path of the leading delivery slide finger, an interchangeable dial lever key adapted to engage a lug on an interchangeable transfer blade, an interchangeable transfer blade adapted to withdraw a channel latch, a neutralizer link operatively connected with a carriage frame and the justification lever adapted to hold the said locking arrangements in neutral when desired, a justification lever movable into and out of the path of the trimming knife sector cover or block adapted to withdraw an outside transfer blade, an outside transfer blade operatively connected with the justification lever and also adapted to move the channel latch to obstructing position when the vise is opened and to move out of engagement with the channel latch when the justification lever is engaged by the sector cover or trimming knife block in normal locked position of the vise frame, a hood operatively connected with the justification lever and the outside transfer blade also adapted to hold the channel latch in perpendicular position.

2. In an automatic liner safety device, adapted to be attached to the lower side of the intermediate channel, the vise locking screws, the mold turning pinion and the dial lever, supporting collars attachable to the vise locking screws adapted to support a timing block mechanism, an intermediate transfer blade operatively connected with a reciprocal register rod and a mold turning pinion also adapted to move the channel latch to obstructing position when the mold turning pinion is revolved with the hand and to move out of engagement with the channel latch when the mold turning pinion is re-seated in normal position by allowing the reciprocal register rod to release it, a reciprocal register rod operatively connected with the adapter slide block and the intermediate transfer blade adapted to engage the said intermediate transfer blade when the mold turning pinion is moved outward to be revolved by hand and to move out of engagement with the said intermediate transfer blade when said mold turning pinion is released or re-seated in normal position, a timing block operatively connected with a supporting collar and the reciprocal register rod adapted to time and control the movement of said reciprocal register rod, an adapter slide block operatively connected with the reciprocal register rod and the mold turning pinion adapted to move the reciprocal register rod with each outward movement of the mold turning pinion, and means of adjusting said adapter slide block; an extension pivot pin operatively connected with the mold turning pinion and the adapter slide block adapted to support the said adapter slide block mechanism.

In testimony that I claim the foregoing as my own, I have hereto affixed my signature.

B. A. MILLS.
